UNITED STATES PATENT OFFICE.

FRANK H. STEIFEL, OF JERSEY CITY HEIGHTS, NEW JERSEY.

LINOTYPE-SLUG.

1,172,914.

Specification of Letters Patent. Patented Feb. 22, 1916.

Application filed June 24, 1915. Serial No. 36,026.

To all whom it may concern:

Be it known that I, FRANK H. STEIFEL, a citizen of the United States and a resident of Jersey City Heights, in the county of Hudson and State of New Jersey, have invented certain new and useful Improvements in Linotype-Slugs, of which the following is a specification.

The main object of my invention is to obviate all danger of "smudging" or soiling the paper during printing by reason of the contact of the paper with the upper quad line edge of the slug below the faces of the type;—and by "type slug," I herein mean to designate a plate of metal with type-high letters or characters cast thereon in the usual way by means of type matrices as in the Mergenthaler and similar linotype machines. Heretofore the upper quad line edges of these type slugs below the type faces, have extended but little below "type-high," which is not objectionable where the solid line is full of type-faces practically from one end to the other. But where either end of the line is lacking to any considerable extent in "type-high" printing surfaces there is danger of the inking of such depressed quad line surface or surfaces of the upper edge of the type slug, and hence of the staining or "smudging" of the paper printed upon. Under present conditions this is a serious obstacle and objection in book work, newspaper work, the printing of testimony, &c., where many lines are only partially set up and occupied by type printing faces,—resulting in inferior prints, frequently to such an extent as to necessitate discardment.

As is well known, in casting the linotype bars or slugs the type matrices are assembled and held closely against the face of the mold, closing the same, and hence the depth of the matrix grooves determines the depth of the front edge of the cast slug below "type-high" *i. e.*, below the faces of the printing type. This difference between type high and the height of the rest of the slug has heretofore been only sufficient to afford a suitable relief base for the type faces, with the resultant defects in printing hereinbefore set forth.

My invention consists in obviating this difficulty by increasing the difference in height between the "type-high" printing faces and the rest of slug especially the quad line or lines sufficiently to remove said

front quad line edge or edges below the said type faces from all danger of contact with ink or paper under ordinary conditions of printing, and this I accomplish by making the matrices deeper and the mold shallower, as herein set forth.

In the accompanying drawings, Figure 1, is a diagrammatic perspective of a mold carrying wheel of well known construction and use in connection with linotype apparatus; Fig. 2, a perspective view of one of the molds; Fig. 3, a side elevation of a type-matrix used in such apparatus; Figs. 4, and 5, respectively front edge and side views of my improved linotype slug.

In the drawings W represents an ordinary mold wheel such as used in "linotype" apparatus, and M, an ordinary mold detached therefrom and shown on a larger scale.

T, is one of a series of ordinary so called type matrices, formed with the upper and lower type case grooves *t*, *t*, in the ordinary manner except that they are made one sixteenth of an inch (more or less) deeper than heretofore,—it being understood that the intaglio outlines of the types are formed in the inner or bottom faces of the grooves in the manner well known in the art. To compensate for this increase of the depth of the type grooves *t*, *t*, I make the cast groove *m*, in the mold M, of correspondingly less depth, so that the resultant cast or type slug S, will be standard "type-high" at the printing surfaces *s*, *s*, but considerably less than type high at other quad line portions *s'*, *s'*, of its front edge, as shown more particularly in Fig. 5, in which the depressions *s*², represent the depth or base line of the letters or characters as distinguished from the quad line portions *s'*, *s'*, of the slug S.

By this simple change in form and manufacture of linotype slugs I attain results of vast importance in this branch of the art of printing, considered in a practical, commercial sense, since all danger of the "smudging" or soiling of the paper printed upon is entirely eliminated because the quad line portions *s'*, *s'*, of the front edge of the slug S, below the printing faces *s*, *s*, are so positioned that contact with inking roller or print paper is rendered impossible under ordinary conditions of use.

There is another incidental advantage attained by my invention, and that is the fact that stereotypes made from my new form of

linotype do not have to be routed out to remove superfluous metal that would otherwise prevent the production of good, clear printing,—thus saving the initial cost of 5 expensive routing mechanism, as well as the cost of skilled labor,—the stereotypes being ready for use as cast.

The spaces between the letters and words of type high printing matter are relatively slight, so much so as to prevent the inking of the intervening parts of the slug. It is only the "quad line" parts of the slugs that are in danger of contacting with ink roller of paper printed upon, and which it is the 10 object of my invention to protect for reasons hereinbefore stated. This depression of the front edge s' , of the quad line must be below the base line s^2 , of the type characters and below the base line of the 15 relief base or pedestal in order to be effective, and by type base line we mean the depth of depression s^2 , between adjacent letters of a word as shown in Fig. 5, of the drawing.

20 I am aware that linotype slugs have been formed with "rule-slots" for the accommo- 25

dation of brass column-rules, for use in the composition of figure table-forms, as in Letters Patent No. 791,165, issued to J. R. Rogers, May 30, 1905, but the slug therein 30 shown is not the equivalent of my invention, the face of the quad line thereon being in line, as usual, with the base line of the characters to be printed from, whereas the whole gist of my invention consists in forming the slug with the quad line s' , below the 35 base line s^2 , of the type characters.

What I claim as my invention and desire to secure by Letters Patent is,

A linotype slug of the character design- 40 nated formed with type high surface printing characters, said printing characters being supported on a pedestal, with the quad line front edge below the base line of 45 said printing characters and below the base line of the pedestal so as to prevent the contact of said quad line edge with ink roller or surface to be printed upon, as set forth.

FRANK H. STEIFEL.
